UNITED STATES PATENT OFFICE

155,284

DESIGN FOR A LAMP BASE

Merton L. Gershun, Chicago, Ill., assignor to Rembrandt Lamp Corporation, Chicago, Ill., a corporation of Illinois

Application April 10, 1948, Serial No. 145,633

Term of patent 7 years

(Cl. D33—14)

To all whom it may concern:

Be it known that I, Merton L. Gershun, a citizen of the United States, residing at Chicago, in the county of Cook and State of Illinois, have invented a new, original, and ornamental Design for a Lamp Base, of which the following is a specification, reference being had to the accompanying drawing, forming part thereof.

In the drawing:

Fig. 1 is a perspective view taken from a position at one side and somewhat in front of a lamp base embodying my new design, the dotted lines being used for illustrative purposes only;

Fig. 2 is a front elevational view of the lamp base shown in Fig. 1;

Fig. 3 is a rear elevational view of the lamp base illustrated in Figs. 1 and 2;

Fig. 4 is a side elevational view of same;

Fig. 5 is a top plan view of my lamp base; and

Fig. 6 is a front sectional view taken substantially at a position indicated by a line 6—6 in

Fig. 5, and in the direction of the accompanying arrows.

I claim:

The ornamental design for a lamp base, substantially as shown and described.

MERTON L. GERSHUN.
